(57) **CLAIM**

The ornamental design for a shoe sole, as shown and described.

DESCRIPTION

FIG. 1 is a first lateral perspective view of a shoe sole showing our new design;

FIG. 2 is a first medial perspective view thereof;

FIG. 3 is a lateral side view thereof;

FIG. 4 is a medial side view thereof;

FIG. 5 is a front view thereof;

FIG. 6 is a rear view thereof;

FIG. 7 is a top view thereof;

FIG. 8 is a bottom view thereof;

FIG. 9 is a second medial perspective view thereof; and,

FIG. 10 is a third medial perspective view thereof.

The dash-dot-dash broken lines immediately adjacent the photographic areas represent a boundary and form no part of the claimed design. The even dashed broken lines shown in the figures illustrate portions of the shoe that form no part of the claimed design.
